PHONOGRAPH TONE ARM

Melvin H. Boldt, Glenview, Ill., assignor to Zenith Radio Corporation, Chicago, Ill., a corporation of Delaware

Filed Jan. 15, 1964, Ser. No. 78,208

Term of patent 14 years

(Cl. D26—14)

FIGURE 1 is a top plan view of a first embodiment of my new design for a phonograph tone arm, this embodiment being distinguished by the essential parallelism of the upper and lower surfaces of the larger housing, by the elongated flange surrounding the connecting arm adjacent that housing, by the absence of ribbing or scoring in the saddle-shaped depression of the smaller housing, and by the longitudinal extent of the depression in the larger housing for nearly the entire length of that housing;

FIGURE 2 is a side elevational view thereof;

FIGURE 3 is a front view thereof;

FIGURE 4 is a rear view thereof;

FIGURE 5 is a top plan view of a second embodiment of my design for a phonograph tone arm, this embodiment being distinguished by the downward flare from the connecting arm of the bottom surface of the larger housing, by the shortened flange surrounding the connecting arm adjacent said housing, by the partial ribbing or scoring of the surface of the saddle-shaped depression of the smaller housing, and by the limited longitudinal extent of the saddle-shaped depression in the larger housing;

FIGURE 6 is a side elevational view thereof;

FIGURE 7 is a front view thereof; and

FIGURE 8 is a rear view thereof.

The dominant features of my design reside in those portions of the drawing shown by means of full lines.

The invention resides in a novel design for a phono-

graph tone arm and is characterized by the provision of two generally rectangular housings, one or both being of upwardly converging cross section, at opposite ends of a thin connecting arm, one of the housings being aligned with the connecting arm and the other housing being inclined with respect to the connecting arm, and by the provision of a generally saddle-shaped depression extending laterally across the upper surface and partially down the side walls of one or both of the housings and optionally provided in whole or in part with closely spaced narrow transverse ribbing or scoring.

I claim:

The ornamental design for a phonograph tone arm, substantially as shown and described.
